UNITED STATES PATENT OFFICE.

GEORGE HUSTON STOUT, OF DENVER, COLORADO.

FENCE-POST.

No. 831,119.

Specification of Letters Patent.

Patented Sept. 18, 1906.

Application filed December 4, 1905. Serial No. 290,256.

To all whom it may concern:

Be it known that I, GEORGE HUSTON STOUT, a citizen of the United States, residing at Denver, in the county of Denver and State of Colorado, have invented a new and useful Fence-Post, of which the following is a specification.

This invention relates to fence-posts, and has for an object to provide a post embodying new and improved features of durability, economy, convenience, and efficiency.

A further object of the invention is to provide a post embodying an angle-iron upright having improved means for securing wires to the angle and with a strip of wood approximately filling the angle and to which boards may be nailed to form a combination-fence or a complete board fence or wind-break.

With these and other objects in view the present invention consists in the combination and arrangement of parts, as will be hereinafter fully described, shown in the accompanying drawings, and particularly pointed out in the appended claims, it being understood that changes in the form, proportion, size, and minor details may be made without departing from the spirit or sacrificing any of the advantages of this invention.

In the drawings, Figure 1 is a perspective view of the improved post with a combination-fence applied thereto. Fig. 2 is a view of the post in rear elevation with the wooden strip omitted. Fig. 3 is a view of the post in rear elevation. Fig. 4 is a transverse sectional view of the improved post.

Like characters of reference indicate corresponding parts in all of the figures of the drawings.

In its preferred embodiment the improved post forming the subject-matter of this application comprises an angle-iron upright formed of a sheet of metal (designated as a whole by 10) and folded at 11, 12, and 13 to form three longitudinally-disposed V-shaped grooves, with the apex 11 of the intermediate V extending reversely to and laterally beyond the sides 14 and 15 of the exterior V's.

Through the material at the apex of the intermediate V are formed a plurality of spaced wire-receiving slots 16, transecting the angle. Within the angle of the intermediate V is slidably inserted a vertical rod 17, disposed between the wires 18 and the apex and whereby the several wires are retained within the slots.

The post for rigidity will preferably taper toward the top, and the lower end will be tapered to a driving-point 19, and wings, as 20, will be struck from the metal to prevent the accidental withdrawal of the post from the ground.

The interior angle of the intermediate V will be approximately filled by a strip of wood or other penetrable material 21, tapered and beveled to substantially conform to the groove and with its end truncated to accommodate the wires 18 and rod 17. The wood strip may be secured within the angle in any approved manner, as by bolting, nailing, or by use of screws, as shown at 22. The wood strip affords means whereby any desired number of boards, as 23, may be secured to the post by nailing in the usual manner and whereby a combination or board fence may be constructed or the post used to support a wind-break or other structure. For use with wire fencing only the wood strips may be omitted and the post used as shown in Fig. 2.

Having thus described the invention, what is claimed is—

1. A fence-post comprising a tapered angle-iron having wire-receiving slots in the angle of the iron, inwardly-struck lips upon the angle-iron and a tapered strip of penetrable material secured within the angle-iron and above the lips.

2. A fence-post comprising an angle-iron having slots in the angle thereof for a portion of its length, a strip of penetrable material secured within the slotted portion of the angle-iron, a rod slidably mounted between said strip and the angle-iron and intersecting the slots.

3. In a fence-post the combination with an angle-iron having wire-receiving slots therein, and inwardly-struck lips upon the angle-iron; of a strip of penetrable material secured within the slotted portion of the angle-iron, a rod interposed between said strip and the slotted angle-iron and intersecting the slots, and a handle at one end of the rod and extending above the post.

In testimony that I claim the foregoing as my own I have hereto affixed my signature in the presence of two witnesses.

GEORGE HUSTON STOUT.
